(57) **CLAIM**

The ornamental design for a cord lock as shown and described.

DESCRIPTION

FIG. 1 is a front view of a cord lock, showing my new design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a front, left side and top perspective view thereof, with the rear, right side and top perspective view being identical;
FIG. 8 is a front, right side and top perspective view thereof, with the rear, left side and top perspective view being identical;
FIG. 9 is a front, left side and bottom perspective view thereof, with the rear, right side and bottom perspective view being identical;
FIG. 10 is a front, right side and bottom perspective view thereof, with the rear, left side and bottom perspective view being identical;
FIG. 11 is a front view of the female portion of the cord lock, shown separated from the male portion for ease of illustration;
FIG. 12 is a rear view thereof;
FIG. 13 is a right side view thereof;
FIG. 14 is a left side view thereof;
FIG. 15 is a top view thereof;
FIG. 16 is a bottom view thereof;
FIG. 17 is a front, left side and top perspective view thereof, with the rear, right side and top perspective view being identical;
FIG. 18 is a front, right side and top perspective view thereof, with the rear, left side and top perspective view being identical;
FIG. 19 is a front, left side and bottom perspective view thereof, with the rear, right side and bottom perspective view being identical;
FIG. 20 is a front, right side and bottom perspective view thereof, with the rear, left side and bottom perspective view being identical;
FIG. 21 is a front view of the male portion of the cord lock, shown separated from the female portion for ease of illustration;
FIG. 22 is a rear view thereof;
FIG. 23 is a right side view thereof;
FIG. 24 is a left side view thereof;
FIG. 25 is a top view thereof;
FIG. 26 is a bottom view thereof;
FIG. 27 is a front, left side and top perspective view thereof, with the rear, right side and top perspective view being identical;
FIG. 28 is a front, right side and top perspective view thereof, with the rear, left side and top perspective view being identical;
FIG. 29 is a front, left side and bottom perspective view thereof, with the rear, right side and bottom perspective view being identical;
FIG. 30 is a front, right side and bottom perspective view thereof, with the rear, left side and bottom perspective view being identical;
FIG. 31 is a front view of a cord lock, showing another embodiment of my design;

FIG. 32 is a rear view thereof;
FIG. 33 is a right side view thereof;
FIG. 34 is a left side view thereof;
FIG. 35 is a top view thereof;
FIG. 36 is a bottom view thereof;
FIG. 37 is a front, left side and top perspective view thereof, with the rear, right side and top perspective view being identical;
FIG. 38 is a front, right side and top perspective view thereof, with the rear, left side and top perspective view being identical;
FIG. 39 is a front, left side and bottom perspective view thereof, with the rear, right side and bottom perspective view being identical;
FIG. 40 is a front, right side and bottom perspective view thereof, with the rear, left side and bottom perspective view being identical;
FIG. 41 is a front view of the female portion of the cord lock of FIG. 31, shown separated from the male portion for ease of illustration;
FIG. 42 is a rear view thereof;
FIG. 43 is a right side view thereof;
FIG. 44 is a left side view thereof;
FIG. 45 is a top view thereof;
FIG. 46 is a bottom view thereof;
FIG. 47 is a front, left side and top perspective view thereof, with the rear, right side and top perspective view being identical;
FIG. 48 is a front, right side and top perspective view thereof, with the rear, left side and top perspective view being identical;
FIG. 49 is a front, left side and bottom perspective view thereof, with the rear, right side and bottom perspective view being identical;
FIG. 50 is a front, right side and bottom perspective view thereof, with the rear, left side and bottom perspective view being identical;
FIG. 51 is a front view of the male portion of the cord lock of FIG. 31, shown separated from the female portion for ease of illustration;
FIG. 52 is a rear view thereof;
FIG. 53 is a right side view thereof;
FIG. 54 is a left side view thereof;
FIG. 55 is a top view thereof;
FIG. 56 is a bottom view thereof;
FIG. 57 is a front, left side and top perspective view thereof, with the rear, right side and top perspective view being identical;
FIG. 58 is a front, right side and top perspective view thereof, with the rear, left side and top perspective view being identical;
FIG. 59 is a front, left side and bottom perspective view thereof, with the rear, right side and bottom perspective view being identical; and
FIG. 60 is a front, right side and bottom perspective view thereof, with the rear, left side and bottom perspective view being identical.
